UNITED STATES PATENT OFFICE.

ROLAND L. SMITH, OF BELMONT, MASSACHUSETTS.

PORTABLE ELECTRIC SEARCHLIGHT.

Application filed February 21, 1924, Serial No. 694,281. Renewed May 25, 1925.

To all whom it may concern:

Be it known that I, ROLAND L. SMITH, a citizen of the United States, and a resident of Belmont, county of Middlesex, State of Massachusetts, have invented an Improvement in Portable Electric Searchlights, of which the following description, in connection with the accompanying drawing, is a specification, like characters on the drawing representing like parts.

This invention relates to improvements in portable electric search lights of the type disclosed in my prior Patent No. 1,170,012, granted Feb. 1, 1916, in which an electric search light comprising a suitable reflector for projecting the rays of light is mounted upon a storage battery which supplies current to the electric light.

One of the objects of the present invention is to provide a battery box or container having a supporting member or a stud projecting outwardly from one of the walls upon which the search light may be mounted, thereby enabling a more compact and serviceable construction to be produced.

Another object of the invention is to provide a battery box or container having a side provided with a metallic reinforcing member having a support or stud projecting through the outer wall of the side, upon which a suitable bracket for the search light may be mounted, the plate serving to reinforce the side upon which it is secured, or preferably embedded, to a sufficient extent to enable the battery to be carried by the handle of the search light without other means of support, thereby avoiding the necessity of providing a strap or other means for carrying the device.

A further object of the invention is to provide a novel form of bracket, for supporting the search light upon the projecting stud, which is so formed that the vertical line of the center of gravity of the apparatus passes through the handle of the search light thereby providing a balanced construction which can be readily carried by the operator.

A further object of the invention is to provide a novel bracket or support between the projecting stud and the search light which enables the beam of the search light to be projected in any desirable direction.

A further object of the invention is to

provide a convenient means by which the search light can be removed from its support and readily manipulated.

A further object of the invention is to provide a search light of the character described having a battery box or container provided with a plurality of oppositely extending supporting studs whereby a plurality of electric lights may be supported upon the same battery thereby providing a construction which portable search light may comprise lights of different characters, such for example as a beam light of a flood light.

By reason of such construction a search light is provided in which a narrow beam of light may be projected at a great distance, or a flood light employed to illuminate a relatively wide area.

Other objects and features of the invention will more fully appear from the following description and the accompanying drawings and will be particularly pointed out in the claims.

The preferred embodiment of the invention is illustrated in the accompanying drawings in which Fig. 1 is a side elevation of the search light mounted upon a battery in the manner above described and also showing in dotted lines a second flood light similarly mounted and adapted to projecting its rays in the opposite direction from those of the light which is illustrated in full lines.

Fig. 2 is a vertical sectional view through one side, preferably one side of the battery container showing a reinforcing plate embedded in the side of the container and having a stud projecting through the outer wall thereof, and,

Fig. 3 is an elevation of the preferred form of the reinforcing plate and stud illustrated in Fig. 2.

The portable search light illustrated in full lines in the accompanying drawing comprises a search light having the usual reflector 1 and lens 2 provided with the usual electric bulb (not shown) and having a stem 3 secured to and extending rearwardly from the reflector 1, a suitable handle 4 being rotatably mounted upon the stem 3 and provided with the usual switch mechanism (not shown) for turning on and off the supply of current to the electric light, through conduc-

tors 5 and 6 which are respectively connected to the terminals 7 and 8 of a suitable storage battery.

The storage battery which is illustrated herein as comprising a plurality of cells is enclosed in a preferably rectangular battery box or container 9 preferably formed of vulcanized rubber composition. One of the principle objects of the invention is to provide means by which the search light can be mounted upon a support extending from a side, preferably an end of the battery box, thereby avoiding the necessity of mounting the support on the top of the battery box or container and also avoiding the necessity of employing straps or other usual means for supporting the device when it is to be transported from place to place.

This is accomplished in the illustrative embodiment of the invention disclosed herein by embedding a metallic plate 10, preferably of triangular form in one or more of the sides, preferably an end or ends of the battery box or container, the plate having a stud 11 projecting through the outer wall of the side or end of the container as illustrated in Fig. 2. The preferred plate which is illustrated in Figs. 2 and 3 is of a skeletonized triangular form having a base 12 extending in parallelism with the upper edge of the side in which it is embedded, with the apex 13 of the triangle extending vertically downward. In order to decrease the weight of metal in the reinforcing plate the edges 14 and 15 may be reduced as by bevelling or the central portion of the plate provided with apertures 16 and 17. It will however be understood that reinforcing plates or other forms of construction may be employed within the spirit of the claims.

In order to support the plate during the molding of the side of the battery box, a boss 18 having a cylindrical depression 19 is provided near the apex to receive a suitable stud to support the plate while the composition is being introduced into the mold, this stud being withdrawn and the aperture in the material produced by it filled in when the material of the container has sufficiently set.

By thus providing the embedded plate in the side or end of the container the wall is greatly reinforced and it is enabled to withstand blows which otherwise might break the side of the container and also provides an anchorage sufficient to enable the battery to be supported from the stud 11.

A further feature of the invention consists in providing a novel device for supporting the search light in such a manner that it can be readily detached and also in such a manner that the rays of the search light may be projected in any desirable direction. As illustrated herein the support for the search light comprises an articulated bracket the

lower section of which comprises a cylindrical portion 18 having a bore to fit upon the stud 11. The cylindrical portion 18 is split and is provided with complementary parallel extensions 19 which are clamped together by a winged screw 20. The lower section of the bracket is also provided with a vertical arm 21 having a laterally extending cylindrical boss 22 which is similarly split and provided with a winged clamping screw 23.

The upper section of the articulated member comprises a standard 24 having a reduced cylindrical end portion 25 adapted to fit within the cylindrical boss 22 of the lower section and to be clamped into position there by a screw 23. The upper end of the standard 24 embraces the stem 3 and is secured thereto in any suitable manner.

The standard 24 is offset to extend somewhat over the battery box so that the vertical line of the center of gravity intersects the handle 4 of the search light thus enabling the search light to be properly balanced so that it can be readily transported from place to place by merely lifting it by the handle 4.

The upper section of the bracket may be rotarily adjusted in a horizontal plane by loosening the screw 23 and rotating the bracket about the vertical axis of the cylindrical extension 25 of the standard 24 so that the ray from the search light may be projected in any desired direction at right angles to the axis of said extension 25. By loosening the screw 20 the search light may also be swung about the axis of the stud 11 thus enabling the beam from the light to be projected in any desirable direction perpendicular to the axis of the stud 11. By reason of these two adjustments therefore about axes at right angles to each other a universal mounting is provided which will enable the beam of the search light to be thrown in any desired direction and by then clamping the screws the beam may be held in any desirable fixed position.

Portable search lights of this character have heretofore been manufactured with reflectors or other projecting apparatus for throwing different characters of lights, for example a beam light in which the rays are projected as nearly as possible in parallelism and other lights which are provided with projecting apparatus having more widely distributing rays. It is desirable that a single apparatus may be provided which will have means for projecting either parallel rays such as a beam light or more divergent rays such as a flood light, and such a construction may be provided by constructing the battery container with a plurality of supports for different lights. This may be accomplished by providing opposite sides, preferably opposite ends of the battery container or box, with supporting plates

and studs upon which the different lights may be mounted in the manner aforesaid. This is illustrated in Fig. 1 in the accompanying drawings in which one of the 5 search lights is illustrated in full lines and the other search light and its mountings in dotted lines. In such constructions the battery box 9 is provided with an embedded reinforcing plate similar to the plate 10 illustrated in Figs. 2 and 3 having a stud 26 projecting through the outer wall of the bracket having mounted upon it an articulated support the lower section 27 of which is rotatably mounted upon the stud 26 and 10 secured by a winged screw 28 as above described and is provided also with a cylindrical boss 29 in which the reduced end portion 30 of the upper section 31 is rotatably secured by a winged screw 32. The upper 15 section or standard 29 is secured to the stem 33 of another light 34 which may be a flood light. The flood light may likewise be supplied from the battery, with current, in the manner above described.

25 In such a construction the device may be carried either by the handle 4 of the beam light or by the handle of the flood light being understood that the supports for the lights are of the same construction and are 30 so designed that the vertical line of gravity of the device will pass through the handle properly balancing the device.

It will be understood that the embodiment 35 of the invention disclosed herein is illustrative and not restrictive and that various changes in form, construction and arrangement of parts may be made within the spirit and scope of the following claims.

Having thus described the invention, what 40 is claimed as new, and desired to be secured by Letters Patent is:

1. A portable electric search light comprising a lamp having a reflector provided with a stem having a handle extending rearwardly therefrom and a battery having a container a wall of which is provided with an embedded plate having a stud projecting from a vertical wall thereof, a standard for said light mounted on said stud engaging 50 said stem and normally positioned to cause the vertical line of the center of gravity of the battery and light to intersect the axis of the handle whereby the device will properly balance when raised by the handle.

55 2. A portable electric search light comprising a lamp having a reflector provided with a stem having a handle extending rearwardly therefrom and a battery having a container a wall of which is provided with an embedded plate having a stud projecting from a vertical wall thereof, a standard 60 for said light pivotally mounted at its lower end on said stud, means for detachably securing said standard to said stud, means 65 upon the upper end of said standard engag-

ing said stem positioned to cause the vertical line of the center of gravity of the battery and light to intersect the axis of the handle whereby the device will properly balance when raised by the handle.

70 3. A portable electric search light comprising a lamp having a reflector provided with a stem having a handle extending rearwardly therefrom and a battery having a container a wall of which is provided with an embedded plate having a stud projecting 75 from a vertical wall thereof, an articulated light-supporting standard having a lower section pivotally mounted on said stem to swing about a horizontal axis and an upper section pivoted upon said lower section to swing about an axis perpendicular to the axis of said stud.

80 4. A portable electric search light comprising a lamp having a reflector provided with a stem having a handle extending rearwardly therefrom and a battery having a container a wall of which is provided with an embedded plate having a stud projecting 85 from a vertical wall thereof, an articulated light-supporting standard having a lower section pivotally mounted on said stem to swing about a horizontal axis, an upper section pivoted upon said lower section to swing about an axis perpendicular to the axis of said stud and means for detachably connecting the upper section of said bracket to the lower section.

90 5. A portable search light construction comprising a battery container formed of rigid insulating material and having a side provided with an embedded plate of metal having a stud projecting through the outer wall of said side to provide a support for a 95 light-supporting member and also capable of affording a support for the battery.

100 6. A portable search light construction comprising a battery container having a side provided with an embedded triangular metallic plate having its base parallel to the upper edge of the container and its apex extending downwardly and a stud projecting 105 from the central portion of said base through the outer wall of said side providing a mounting or a light-supporting member.

110 7. A portable search light construction comprising a battery container having a side provided with an embedded plate of triangular form having a central aperture therethrough the walls of said plate being beveled toward said aperture and the base of said plate lying in parallelism with the upper wall of the receptacle and the apex 115 of the plate extending downwardly, said base having a stud projecting through the outer wall of the side providing a mounting or a light-supporting member.

120 8. A portable search light construction comprising a rectangular battery container 125

having its opposite sides each provided with an embedded metallic plate having a stud projecting through the outer wall of the side providing a mounting or a light-supporting member.

9. A portable search light construction comprising a rectangular battery container having its opposite sides provided with embedded triangular plates with their bases lying oppositely to the upper edge of the container and their apexes extending downwardly and with studs projecting from the central portions of said bases through the outer walls of sides providing a mounting or a light-supporting member.

10. A portable electric search light comprising a plurality of lamps having different

means for projecting rays of light and provided with handles extending rearwardly from the projecting means and a battery 20 having a container the opposite walls of which are provided with embedded plates having studs projecting outwardly from the walls thereof, articulated standards for the respective lights mounted upon said studs, 25 so constructed that the vertical line of the center of gravity of the assembled apparatus may be caused to intersect one of the handles of said lights, whereby the device will be properly balanced when lifted by one of said 30 handles.

In testimony whereof, I have signed by name to this specification.

ROLAND L. SMITH.

having its opposite sides each provided with an embedded metallic plate having a stud projecting through the outer wall of the side providing a mounting or a light-supporting member.

9. A portable search light construction comprising a rectangular battery container having its opposite sides provided with embedded triangular plates with their bases lying oppositely to the upper edge of the container and their apexes extending downwardly and with studs projecting from the central portions of said bases through the outer walls of sides providing a mounting or a light-supporting member.

10. A portable electric search light comprising a plurality of lamps having different

means for projecting rays of light and provided with handles extending rearwardly from the projecting means and a battery 20 having a container the opposite walls of which are provided with embedded plates having studs projecting outwardly from the walls thereof, articulated standards for the respective lights mounted upon said studs, 25 so constructed that the vertical line of the center of gravity of the assembled apparatus may be caused to intersect one of the handles of said lights, whereby the device will be properly balanced when lifted by one of said 30 handles.

In testimony whereof, I have signed by name to this specification.

ROLAND L. SMITH.

Certificate of Correction.

It is hereby certified that in Letters Patent No. 1,544,191, granted June 30, 1925, upon the application of Roland L. Smith, of Belmont, Massachusetts, for an improvement in "Portable Electric Searchlights," errors appear in the printed specification requiring correction as follows: Page 3, lines 115 and 128, claims 6 and 7, and page 4, lines 4 and 15, claims 8 and 9, for the word "or" read for; page 4, line 12, claim 9, for the word "study" read studs; and line 14, before the word "sides" insert the word said; and that the said Letters Patent should be read with these corrections therein that the same may conform to the record of the case in the Patent Office.

Signed and sealed this 21st day of July, A. D. 1925.

[SEAL.]

KARL FENNING,
Acting Commissioner of Patents.

Certificate of Correction.

It is hereby certified that in Letters Patent No. 1,544,191, granted June 30, 1925, upon the application of Roland L. Smith, of Belmont, Massachusetts, for an improvement in "Portable Electric Searchlights," errors appear in the printed specification requiring correction as follows: Page 3, lines 115 and 128, claims 6 and 7, and page 4, lines 4 and 15, claims 8 and 9, for the word "or" read *for*; page 4, line 12, claim 9, for the word "study" read *studs*; and line 14, before the word "sides" insert the word *said*; and that the said Letters Patent should be read with these corrections therein that the same may conform to the record of the case in the Patent Office.

Signed and sealed this 21st day of July, A. D. 1925.
